FREDERICK G. NIEDRINGHAUS AND WILLIAM F. NIEDRINGHAUS,
OF ST. LOUIS, MISSOURI.

Letters Patent No. 85,843, dated January 12, 1869.

IMPROVEMENT IN MANUFACTURE OF CURVED ELBOWS.

The Schedule referred to in these Letters Patent and making part of the same.

To all whom it may concern:

Be it known that we, FREDERICK G. NIEDRINGHAUS and WILLIAM F. NIEDRINGHAUS, of the city and county of St. Louis, in the State of Missouri, have invented a new and useful Improvement in the Manufacture of Curved Elbows for Stove-Pipes; and we do hereby declare the following to be a full and exact description thereof, reference being had to the accompanying drawings, forming a part of this specification, in which—

Figure 1 is a plan of the form of metal-blank, out of which the elbows are stamped;

Figure 2, an elevation of our improved curved elbow; and

Figure 3, a transverse section in the line xx of fig. 2, with the thickness of the metal greatly exaggerated.

The nature of our invention consists in the formation of curved elbows for stove-pipes, by stamping up two longitudinal halves or sections from metallic blanks, slitted in that portion thereof which is to constitute the inner part of the curve therein, so that the surplus of metal in the curve shall be taken up by overlapping at the slits, and uniting the said halves by a suitable lock-joint.

In the accompanying drawings—

A represents a metal-blank, of suitable form, for the half of an elbow.

b b, the slits cut therein, from a point approaching the edge of the inner, and extending about midway to the outer edge. The number of the slits may be greater or less, but we have found three of them sufficient in elbows made of ordinary metal.

The blank, A, properly shaped and slitted, is next placed between suitable metallic dies, and stamped between them into the longitudinally-curved form required in the elbow, and with a semicircular section.

In being thus bent and curved into shape, the excess of metal, in the inner portion of the curve along each of the slits, is taken up by the overlapping of one side of the slit over the opposite edge thereof, as indicated by the dotted lines in fig. 2, so that a regular, even, finished curve is obtained on the under or inner as

well as the upper side of each section of the elbow, without straining, breaking, or crimping the metal.

The edges of each half or section are folded or bent over into a hooked shape, (as indicated in fig. 3 of the drawings,) so far as the curve extends, the remaining portion at each end being left projecting to overlap a corresponding plain edge on the opposite section. The two sections are united by interlocking their hooked edges, as shown in said fig. 3, and then riveting the overlapping edges at each end to complete the elbow.

The ends of the elbow, formed by the overlapping edges of the two divisions, are respectively enlarged, (see a, fig. 2,) to pass over the next lower straight section, B, of the stove-pipe, upon which the elbow is to be placed, and contracted (see a', fig. 2) to enter the horizontal section of pipe, C, to be placed thereon.

As the metal is left in its normal state, and is not subjected to excessive strain in the formation of our improved curved elbows, as herein described, a cheaper quality of iron may be used in their manufacture, and their cost thus greatly reduced.

The longitudinal divisions of which they are composed can be closely packed for transportation, and be readily put together for use and sale as required, after having reached their destination, thus lessening the cost of shipping them from point to point.

Having thus fully described our invention,

We claim therein as new, and desire to secure by Letters Patent—

A curved stove-pipe elbow, constructed in two longitudinal divisions, wherein the surplus metal of the inner curve thereof is taken up by the overlapping of the edges of one or more transverse slits in said divisions, substantially in the manner herein set forth.

The foregoing specification of improved stove-pipe elbow signed, this 19th day of November, 1868, in the presence of—

F. G. NIEDRINGHAUS.

Witnesses: WM. F. NIEDRINGHAUS.

CHARLES F. BAUER,

JOS. P. MAULL.
